UNITED STATES PATENT OFFICE.

LOUIS H. WELLENSIEK, OF HOUSTON, TEXAS, ASSIGNOR TO HUGHES TOOL COMPANY,
OF HOUSTON, TEXAS, A CORPORATION OF TEXAS.

SOFT-FORMATION CORE DRILL.

Application filed August 2, 1926. Serial No. 126,471.

My invention relates to core drills for cutting soft formation encountered in well drilling.

It is an object of the invention to construct a core drill adapted to cut the softer grades of material in well drilling, which drill will be balanced in its construction and hence will be enabled to operate smoothly and evenly.

10 It is also desired to discharge the flushing fluid directly in front of each cutting element and in the direction of inclination of the cutter.

15 It is a further object to form a detachable core catcher seat which will assist in maintaining the core from contact with the wash of the flushing fluid.

Referring to the drawing herewith, Fig. 1 is a side view partly in elevation and partly in section on the line 1—1 of Fig. 2. Fig. 2 is a bottom plan view of the drill. Fig. 3 is a side view, partly in section, of the core catcher seat, removed. Like numerals of reference are applied to like parts in all 25 the views.

In carrying out my invention I provide a tubular head 1, having an upper threaded socket 2 thereon to receive the drill collar 3, through which the drill may be rotated. 30 The lower end of the head is provided with teeth cut into the wall of the head. These teeth are arranged in two sets of three cutters in each set. There is one set of teeth 4 which are inclined outwardly and one set 5 which are inclined inwardly.

The manner of forming the teeth is to be noted. They are cut deeply upward into the wall of the drill, the upper end 6 of the recess between adjacent teeth being shown in Fig. 1. The forward side of the adjacent tooth is cut away at 7 to form a shoulder and below the shoulder the flat forward face 8 of the tooth extends down to a cutting point 9 which is inclined forwardly.

45 The flushing fluid is discharged to the cutters through channels 10 issuing through outlets in the shoulders 7 of the teeth and, by noting the sectioned portion of Fig. 1, it will be seen that, when the tooth is bent to incline it inwardly or outwardly, as the case may be, the water channels are also bent to provide a discharge of the water along the face of the cutter parallel therewith.

The core barrel 11 has a collar 12 secured 50 at its lower end, said collar being threaded

to engage the inner threaded wall 13 of the drill.

The core catcher seat 14 is formed of a thin sleeve of steel the walls of which are tapered downwardly except for a short cylindrical portion 15 at the upper end. The seat fits the lower inner face of the drill and the teeth 5 of the drill which are inclined inwardly, form a support for the tapered portion of the seat, the portion 15 fits the inner drill wall above the teeth. The seat is held removably in position by the lower end of the core barrel collar 12.

The core catching jaws 16 are mounted on a spring collar 17 fitting the seat 14 in any 70 preferred manner. It is to be noted that the seat 14 will enclose the lower end of the core between the teeth and protect it from the wash of the flushing water.

As will be seen from Fig. 2, the points 75 of the teeth are bent forwardly and the edges are also inclined backwardly away from a radial line, to better accomplish a shearing action on the material and allow the material to be moved away from the cutting points 80 9. This keeps the cutting points clear of material and moves the cuttings into the path of the flushing fluid.

In operation the rotation of the drill in a clockwise direction, as viewed from above, 85 will force the teeth into the formation cutting off portions of the material and the streams of flushing fluid directed along the faces of the cutters will carry the cuttings upwardly and flutes or grooves 19 in the 90 outer side of the head allow passages for the same. The core is protected from being washed by the flushing fluid by the core catcher and its seat extending downwardly inside the teeth to the points of the cutting 95 teeth.

Having thus described the invention what I claim as new and desire to protect by Letters Patent is:

1. A core drill including a tubular head, 100 teeth cut deeply into the lower wall thereof, each alternate tooth being bent inwardly forming a support, a core catcher sleeve tapered to fit within the support formed by said teeth, said sleeve extending downwardly 105 to a plane adjacent the cutting edges of said teeth to close the space between adjacent teeth, means to discharge flushing fluid outside said sleeve, and core engaging means in said sleeve.

2. A core drill including a tubular head, teeth cut deeply into the lower wall thereof, each alternate tooth being inclined inwardly, a core catcher sleeve tapered to fit the supports provided by said inwardly inclined teeth, said sleeve closing the space between said teeth from a line above said teeth to a

level closely adjacent the lower ends thereof, said sleeve being also adapted to receive core engaging elements.

10

In testimony whereof I hereunto affix my signature this 26th day of July A. D. 1926.

LOUIS H. WELLENSIEK.
